UNITED STATES PATENT OFFICE.

FRANK H. CRUMP, OF LOS ANGELES, CALIFORNIA.

LOOSE-LEAF BINDER.

Application filed August 31, 1927. Serial No. 216,707.

My invention relates to loose leaf binders of the character embodied in my co-pending application, Serial No. 186,723, filed April 26, 1927. In this type of binder a cover is provided composed of sections which are extensibly connected to a back section for the purpose accommodating variable numbers of leaves or sheets and held in binding relation to the latter by straps extended into and secured in pockets pinched in the back edges of the sheets. The straps which are usually formed of metal are associated with the cover to hold the sections in adjusted position, and to effect a new adjustment of the cover sections as required when the number of sheets is appreciably increased, it is necessary to detach the straps by removing a locking rod, shift the straps to the position desired, and replace the locking rod in order to maintain the straps in the newly adjusted position. Also, to secure the cover to the sheets, it is necessary to operate a locking mechanism thus impeding release of the cover when it is desired to insert additional sheets or to remove any of the present sheets. Each time a lock or release of the cover in respect to the sheets is made, bending of the strap is required and as they are formed of metal, repeated bending and straightening soon causes them to split or break thus necessitating new straps.

It is a purpose of my invention to provide a loose leaf binder which overcomes the above recited disadvantages by substituting rigid telescopic or otherwise extensibly connected members for the straps, connecting the members directly to the top and bottom cover sections, and connecting such sections to the back section by resilient elements which operate automatically to adjust the cover to accommodate variable numbers of sheets in accordance with an adjustment of the telescopic members.

I will describe only one form of loose leaf binder embodying my invention and will then point out the novel features in claims.

In the accompanying drawings:

Fig. 1 is a view showing in perspective one form of loose leaf binder embodying my invention in closed position and in binding relation to a plurality of sheets or leaves;

Fig. 2 is a view showing the binder in top plan and open, with a portion of the sheets broken away to reveal parts not otherwise disclosed;

Fig. 3 is a fragmentary plan view of the

binder in open position and with the top cover section released to permit removal of the sheets from the binder;

Fig. 4 is a vertical sectional view taken on the line 4—4 of Fig. 5 and showing the top cover section in open position;

Fig. 5 is a view showing the binder in rear elevation with the back cover section in vertical section;

Fig. 6 is an enlarged detail perspective view of the bottom post bar embodied in the binder;

Fig. 7 is an enlarged view showing in side elevation, with portions thereof broken away, one of the cover section connectors embodied in the binder;

Figs. 8 and 9 are sectional views taken on the lines 8—8 and 9—9 of Fig. 7;

Fig. 10 is a fragmentary vertical sectional view taken on the line 10—10 of Fig. 3; and

Fig. 11 is a view showing in perspective the entire binder with the main parts thereof separated but in proper positions for association with a plurality of leaves.

Similar reference characters refer to similar parts in each of the several views.

Referring specifically to the drawings, my invention, in its present embodiment, comprises a cover including rigid top and bottom sections T and B, respectively, and a flexible back section F, which serves to connect the other two sections to form a cover for a plurality of sheets of paper S which is capable of being opened and closed in the manner of a book. The sections T and B are constructed to provide compartments 15 and 16 therein opening into the inner ends of the sections and into which the ends of the back section F are extended and movable, all in a manner to allow a longitudinal adjustment of the top and bottom sections on the back section so as to vary the spacing of the confronting ends of the top and bottom sections and to thereby vary the capacity of the binder as a whole to accommodate any number of sheets S, i. e. within certain limits.

As shown in Figs. 2 and 3, relatively small plates 17 are riveted within the compartments 15 and 16, and similar plates 18 are riveted to the opposite ends of the back section F. These plates 17 and 18 are provided with hook-shaped ears 19 by which coiled contractible springs 20 are secured to the plates in the manner illustrated and for the purpose of yieldably urging the sections T and B inwardly upon the section F. The

sections T and B are slotted, as indicated at 21, in order to facilitate riveting of the plates 17 and 18 and exposing the plates and springs to permit application of the springs to the 5 plates and to insure the required freedom of movement of the springs as will be understood.

Riveted to the inner sides of the top and bottom sections T and B and at the confronting ends thereof are a pair of plates P and P', respectively, formed of metal or other suitable material and constituting stationary hinge leaves with their edges constructed to provide knuckles 22 arranged in pairs and 15 having pintles 23 extended through each pair. The pintles are also extended through knuckles 24 and 25 on the outer ends of members 26 and 27, respectively, telescopically associated with each other and constituting 20 adjustable connectors by which the top and bottom cover sections are adjustably connected to each other.

In the present instance I have shown two such connectors, the members 27 of each connector being extended into the member 26 and carrying a spring pawl 28 urged into engagement with two sets of ratchet teeth 29 on the inner side of the member 26. This pawl in engaging the sheet 29 normally acts 30 to secure the members against movement outwardly from each other, but the pawl can be moved to a released position by the provision of a button 30 which projects through a slot 31 in the member 26 so as to be engaged by 35 the finger and forced inwardly until the pawl is free of the teeth, when the members can be moved laterally and longitudinally to increase or decrease their overall length and thereby vary the spacing of the top and bottom cover sections with respect to each other. 40

These connectors are designed primarily to coact with a locking means for adjustably securing the sheets S within the cover and upon posts provided for the purpose. A 45 lower pair of posts 32 rise from a bottom bar 33, and this bar, as shown in detail in Fig. 3, is provided with knuckles 34 through which the pintle for the plate P' extends thereby hingedly connecting the bar to the plate. An 50 upper pair of posts 35 depends from the stationary section 36 of a top bar. This top bar is constructed in the same manner as the top bar disclosed in my application hereinbefore referred to and includes a movable or latch 55 section 37 having pin and slot connections 38 with the stationary section so as to be capable of sliding movement thereon and to either of two extreme positions. The sections 36 and 37 are recessed to provide pockets 39, the movable section having latching fingers 40 adapted to engage and confine the connectors within the pockets. In one extreme position of the movable section the pockets 39 are open to permit the insertion or withdrawal of the connectors, but in the other 60

extreme position the pockets are closed by the finger 40 to confine the connectors therein. The movable section can be actuated by the provision of a button 41 secured thereon.

The manner in which the bottom and top bars are adapted to be associated with the sheets S is clearly illustrated in Figs. 5 and 11, the sheets being provided with openings 70 to receive the posts 32 and 35 and thus maintain them in stacked relation.

The connectors are adapted to be received within grooves or pockets 43 in the back edges of the sheets S, and when the pockets 39 of the top bar are closed with the fingers 40, it will be clear that the connectors are secured within the grooves or pockets, all as 75 clearly illustrated in Fig. 4.

In the operation of the binder the sheets S are first applied to the lower posts 32, followed by an application of the upper posts 35 so that the upper bar is positioned upon the top of the sheets with the pockets 39 of the stationary section 36 in registration with the pockets 43 of the sheets. In this manner the several sheets are held in proper stacked position within the cover. To secure them 80 therein the top cover section T is elevated from the position shown in Fig. 3 to that shown in Figs. 2 and 4 in which the connectors are swung to vertical position and within the pockets 39. By now moving the section 37 from the position shown in Fig. 3 to that shown in Fig. 4 the fingers 40 will 85 close the pockets and thus confine the connectors therein. Thus, the sheets are secured in stacked relation within the cover 90 while the cover sections T and B through their hinged connections with the connectors 95 are free to be swung to open or closed position.

By constructing the connectors of extensible or telescopic members their overall length can be varied as desired through manipulation of the pawls 28 in the manner 100 previously described, and to thereby vary the spacing of the covers T and B to accommodate any number of sheets S. Should the number of sheets be increased or decreased 105 from that shown the connectors can be lengthened or shortened accordingly, the springs 20 freely responding to such adjustment of the connectors in order to permit the required movement of the sections T and B upon the section F. In other words, as the 110 top and bottom sections are moved outwardly, for example, upon the back section T, the springs 20 will be extended to permit such relative movement, and conversely as the sections T and B are moved inwardly upon the 115 back section the springs will contract, thus at all times preventing gathering or folding of the back section.

In actual practice, the buttons 30 can be 120 simultaneously pressed with the fingers to 125

release the pawls 28 to permit the required adjustment of the cover sections to accommodate any particular number of sheets. Such adjustment is generally in excess of that 5 actually required in order to permit the free insertion of the connectors within the pockets of the sheets and the top bar. After the connectors have been inserted into the pockets, the top section, which is now in substantially vertical position is pressed downwardly with sufficient force to cause the members 26 and 27 to slide one upon the other until the inner edge of the upper plate P comes into contact with the movable section 37 10 when the section 37 is moved to secure the connectors within the pockets. By operating the binder in this manner the cover is adjusted to snugly fit the sheets therein so as to cause all of the sections to lie contiguous to 15 the sheets.

When desiring to release the sheets, the connectors can be readily removed from the pockets by sliding the section 37 to the position shown in Fig. 3, and by removing the 25 top bar together with its posts 35, direct access can be had to the sheets to permit the addition of new sheets or removal of any of the old sheets.

Although I have herein shown and 30 described only one form of loose leaf binder embodying my invention, it is to be understood that various changes and modifications may be made herein without departing from the spirit of the invention and the spirit and 35 scope of the appended claims.

I claim:

1. In a loose leaf binder, a cover having 40 top and bottom sections and a flexible back section, a yieldable connection between the back section and the top and bottom sections, members hingedly connected to the top and bottom sections and telescopically associated with each other with pawl and ratchet means 45 for securing the members in adjusted position to maintain the top and bottom sections in a predetermined spaced relation, sheets between the top and bottom sections having edge pockets in which said members are received, a bar hinged on the bottom section 50 and carrying posts extending into the sheets, and a top bar having posts extending into the sheets and comprising a stationary part and a movable part slidable on the latter, both of said parts having pockets adapted to register 55 with the sheet pockets so as to receive said members, the movable part having fingers for closing the bar pockets and retain the members within the sheet and bar pockets.

2. In a loose leaf binder as embodied in 60 claim 1 wherein a button is provided on the movable part for actuating the latter, and a spring latch engages the button for retaining the movable part in a predetermined position.

3. In a loose leaf binder, top and bottom

cover sections, a back section secured to the cover sections, separate connectors hingedly secured at each end to the cover sections, leaves pocketed to receive the separate connectors, a bar hingedly secured to the bottom 70 cover section and having posts extending upward into the leaves, an independent bar applicable to the leaves and having posts extending downward into the leaves and coacting with the upstanding posts to secure the 75 leaves within the cover, and means on the independent bar for releasably securing it to the separate connectors.

4. In a loose leaf binder as embodied in 80 claim 3 wherein the separate connectors and the bottom post bar are provided with hinge eyes through which they are secured to the bottom cover by means of the same hinge pin.

5. In a loose leaf binder, top and bottom 85 cover sections, a back section secured to the cover sections, extensible connectors hingedly secured at each end to the cover sections, releasable means on each extensible connector for locking it in adjusted position, leaves pocketed to receive the extensible connectors, 90 leaf holding means hingedly secured to the bottom cover section, independent leaf holding means releasably secured to the extensible connectors, co-acting with the first leaf holding means to retain the leaves in the 95 binder.

6. In a loose leaf binder, top and bottom 100 cover sections, a back section secured to the cover sections, extensible connectors hingedly secured at each end to the cover sections, releasable means on each extensible connector for locking it in adjusted position, leaves pocketed to receive the extensible connectors, leaf holding means hingedly secured to the bottom cover section, independent leaf holding 105 means releasably secured to the extensible connectors co-acting with the first leaf holding means to retain the leaves in the binder, the bottom leaf holding means being secured to the bottom cover section by the 110 hinge pin which also secures the extensible connectors to the bottom cover section.

7. In a loose leaf binder, top and bottom 115 cover sections, a back section secured to the cover sections, extensible connectors hingedly secured at each end to the cover sections, releasable means on each extensible connector for locking it in adjusted position, leaves pocketed to receive the extensible connectors, leaf holding means hingedly secured to the bottom cover section, independent leaf holding 120 means releasably secured to the extensible connectors and co-acting with the first leaf holding means to retain the leaves in the binder, the hinged mounting of the extensible connectors being located to allow said connectors to be held in alignment with the leaf holding means when secured to the independent leaf holding means and to occupy a position substantially at right angles to the leaf 125 130

holding means when released from the independent leaf holding means.

8. In a loose leaf binder, top and bottom cover sections, a back section secured to the cover sections, extensible connectors hingedly secured at each end to the cover sections, releasable means on each extensible connector for locking it in adjusted position, the releasable means being independent of the cover sections or the back section, leaves pocketed to receive the extensible connectors, an element independent of the extensible connectors and hingedly secured to the bottom cover section and having posts extending upward into the leaves, an independent element applicable to the leaves and having posts extending downward into the leaves and co-acting with the upstanding posts to secure the leaves within the cover and means on the independent element for releasably securing it to the extensible connectors.

9. In a loose leaf binder, top and bottom cover sections, recesses in the cover sections, a flexible back section adjustably secured in the cover recesses, extensible connectors hingedly secured at each end to the cover sections, releasable means on each extensible connector for locking it in adjusted position, the releasable means being independent of the cover sections or the back section, leaves pocketed to receive the extensible connectors, a bar independent of the extensible connectors and hingedly secured to the bottom cover section and having posts extending upward into the leaves, an independent bar applicable to the leaves and having posts extending downward into the leaves and co-acting with the upstanding posts to secure the leaves within the cover and means on the independent bar for releasably securing it to the extensible connectors, such releasable means comprising a stationary part and a movable part slidable on the former, both of said parts having pockets registering with the leaf pockets and adapted to receive the extensible connectors, the movable part having fingers for closing the bar pockets and retaining the extensible connectors within the bar pockets and the leaves.

10. In a loose leaf binder as embodied in claim 9, wherein a spring latch is provided on the independent bar for retaining the movable part in a predetermined position with relation to the stationary part.

11. In a loose leaf binder, top and bottom cover sections, recesses in the cover sections, a flexible back section adjustably secured in the cover recesses, extensible connectors provided with hinge eyes for permanently connecting the cover sections, each connector comprising a ratchet member hingedly connected to one of the cover sections and a pawl member hingedly connected to the other cover section and telescoping into and permanently held by the ratchet member, means on the

pawl member for adjustably locking it to the ratchet member to maintain an extended relation of the cover sections to each other, leaves pocketed to receive the extensible connectors, a bar independent of the extensible connectors and provided with hinge eyes by means of which it is secured to the bottom cover section with the hinge pin which also secures the extensible connectors to the bottom cover section, the bar having posts extending upward into the leaves, an independent bar applicable to the leaves and having posts extending downward into the leaves and co-acting with the upstanding posts to secure the leaves within the cover and means on the independent bar for releasably securing it to the extensible connectors.

12. In a loose leaf binder, top and bottom cover sections extensibly and permanently connected, a back section secured to the cover sections, means independent of the back section for securing the cover sections in adjusted position in accordance with the number of leaves between the sections, said means being hingedly connected at each end to the cover sections, rigid and engageable within the leaves, an element hingedly secured to the bottom cover section and having posts extending upward into the leaves, an independent element applicable to the leaves and having posts extending downward into the leaves and co-acting with the upstanding posts to maintain the leaves in stacked relation within the cover and means on the independent element for releasably securing it to the first mentioned means, thereby securing the leaves in the cover.

13. In a loose leaf binder, cover sections and a back section, pocketed leaves between the covers, extensible means independent of the back section for securing the covers in adjusted position in accordance with the number of leaves between the covers, said means consisting of extensible posts hinged at each end to the covers and engaging within the pockets of the leaves, independent releasable means for positively locking the leaves to the extensible posts and thereby locking the leaves in the cover.

14. In a loose leaf binder, top and bottom cover sections extensibly and permanently connected, a back section secured to the cover sections, ratchet posts hingedly secured at each end to the cover sections, releasable means on each ratchet post for locking it in adjusted position, pocketed leaves between the top and bottom covers into which said ratchet posts are adapted to be extended, a bar independent of the ratchet posts and hingedly secured to the bottom cover section and having posts extending upward into openings in the leaves, an independent top locking bar having depending posts applied to other openings in the leaves and co-acting with the upstanding posts to secure

the leaves within the cover, means on the independent top locking bar for releasably securing it to the ratchet posts within the pockets of the leaves and to thereby secure 5 the leaves in the covers.

15. In a loose leaf binder, top and bottom cover sections, a flexible back section adjustably secured in the top and bottom covers, ratchet posts hinged to and permanently connecting the covers, releasable means on each ratchet post for locking it in adjusted position, pocketed leaves between the top and bottom covers into which said ratchet posts are adapted to be extended, a bar independent 10 of the ratchet posts and hingedly secured to the bottom cover sections and having upstanding posts extending into closed openings in the leaves, an independent top locking bar having depending posts applied to 15 other closed openings in the leaves and co-acting with the upstanding posts to secure the leaves within the cover, means on the independent top locking bar for releasably securing it to the ratchet posts within the pockets of the leaves and to thereby secure the leaves in the covers, said top locking bar having pockets for the ratchet posts and movable fingers adapted to engage and disengage the ratchet posts to secure the ratchet 20 posts within the pockets of the top locking bar and in the leaves.

16. In a loose leaf binder, top and bottom cover sections extensibly and permanently connected, recesses in the covers, a flexible back section adjustably secured in the cover recesses, hinge plates provided with hinge eyes and secured to the top and bottom covers, ratchet posts provided with hinge eyes at each end through which they are secured to the hinge plates with hinge pins, releasable means on each ratchet post adjustable to the number of leaves to be secured in the binder, pockets in the leaves into which the ratchet posts are adapted to be extended, a bar provided with hinge eyes and secured to the bottom cover hinge with the hinge pin which also secures one end of the ratchet posts to

the bottom cover, the bar being provided with upstanding posts extending into closed openings in the leaves, an independent top locking bar provided with pockets for the ratchet posts and depending posts extending into other closed openings in the leaves, and co-acting with the upstanding posts to secure the leaves within the cover, means on the independent top locking bar movable to secure it to the ratchet posts within the pockets on the bar and in the leaves and to thereby secure the leaves in the binder covers.

17. In a loose leaf binder, top and bottom cover sections extensibly and permanently connected, recesses in the cover sections, a flexible back section adjustably secured in the cover recesses, hinge plates provided with hinge eyes and secured to the top and bottom covers, ratchet posts provided with hinge eyes at each end through which they are secured to the hinge plates of the top and bottom covers by means of hinge pins, releasable means on each ratchet post adjustable to the number of leaves to be secured in the binder, pockets in the leaves into which the ratchet posts are adapted to be extended, a bar having hinge eyes through which it is secured to the bottom cover hinge by the hinge pin which also secures one end of the ratchet posts to the bottom cover, the bar being provided with upstanding posts extending into closed openings in the leaves, an independent top locking bar provided with pockets for the ratchet posts and depending posts extending downward into other closed openings in the leaves and co-acting with the upstanding posts to secure the leaves within the cover, means on the independent top locking bar movable to secure the ratchet posts within the pockets on the bar and in the leaves and to thereby secure the leaves in the binder, means on the top locking bar for releasably holding it in a locked position to prevent accidental disengagement of the ratchet posts.

FRANK H. CRUMP.
